APPLICATOR

Augustine M. Mazzarelli, New York, N. Y., assignor to Henry L. Burkitt, New York, N. Y.

Application January 17, 1942, Serial No. 427,106

10 Claims. (Cl. 15—139)

1

This invention relates to applicators.

The smooth surface of a body molded from plastic material such as cellulose acetate and the like has been found to possess the property of shedding fluids. Thus, the use of such substances for defining applicator faces for use in connection with substances such as mucilage and glue, produces the results, when applying mucilage or similar material to a surface, that the applicator face is wiped substantially clean by the mucilage-applying operation. If mucilage, glue or similar substance should dry upon a face formed from such material, the face may be cleaned readily. For instance, such material, when it dries, will separate from the surface almost of itself, and flake or chip off. The necessary mucilage, glue or similar material must be fed to such an applicator face so that the contents of the bottle or similar source of supply will not be so open to the air as to dry out rapidly.

It is an object of the invention to provide an applicator, for use with a bottle or similar reservoir of mucilage or similar material, wherein the face of the applicator is defined by a surface molded from a plastic such as cellulose acetate or similar material, and wherein provision is made, by means of a dispensing device, to feed mucilage or similar substance positively to the applicator face when the applicator is positioned in spreading position.

It is an object of the invention to provide an applicator head for a container, wherein such head is made substantially of molded plastic material, and has means for ejecting a charge of mucilage or similar material positively when a face of such head is brought into spreading position relative to a surface.

It is an object of the invention to provide positive means for ejecting mucilage from a bottle or similar container, in which the construction of the ejecting means is such that charges of mucilage may not be retained, as, for instance, by pockets, and so that necessarily all excess mucilage not ejected by the means returns into the body of the bottle, to a position where it may not affect the further operation of the ejecting means.

Other objects of this invention will be set forth hereinafter, or will be apparent from the description and the drawings in which are illustrated embodiments of apparatus for carrying out the invention.

The invention, however, is not intended to be restricted to any particular construction, or to any particular arrangement of parts, or to any

2

particular application of any such construction or any such arrangement of parts, or to any specific method of operation, or to any of the various details thereof, even where specifically shown and described herein, as the same may be modified in various particulars, or may be applied in many varied relations, without departing from the spirit and scope of the claimed invention, practical constructions embodying certain details of the invention being illustrated and described, but only for the purpose of complying with the requirements of the statutes for disclosure of operative embodiments, and without attempting to disclose all of the various forms and modifications in which the invention might be embodied.

On the drawings, in which the same reference characters refer to the same parts throughout, and in which are disclosed such practical constructions:

Fig. 1 is an elevational view of a container with an applicator head applied thereon, the applicator head embodying features of the invention, a portion of the container being broken away;

Fig. 2 is a view substantially in cross-section on the line 2—2 of Fig. 1, a part of the container being shown in elevation;

Fig. 3 is a plan view of the construction shown in Fig. 2;

Fig. 4 is a perspective view of the part of the applicator head shown in Fig. 2; and

Fig. 5 is a view in cross-section, along a plane similar to Fig. 2 of, an applicator head of modified construction.

The bottle 10 illustrated on the drawings may be of any desired construction to provide a reservoir for mucilage 12 or similar material. The bottle may have a neck 14, on which an applicator head 16 may be engaged by means such as threads 18 in the open end 20 of the head and on the neck. Bottle 10 and head 16 may be of any desired material; however, it has been found desirable to make head 16 by molding it from plastic material such as cellulose acetate or the like. Such molding operation may include the formation of means such as threads 18 in open end 20.

Head 16 is constructed to provide a hollow section 22, on the outer walls 24 of which an applicator face 26 and an end face 28 may be defined. An opening 30 may extend from end face 28 into hollow section 22, and adjacent side wall 32. The engaging head 34 of a plug 36 may extend through opening 30, and, when the plug projects as shown in Fig. 2, and head 16 is brought into

proximity to a surface, the plug will be engaged against that surface. When plug 36 is fully extended as shown in Fig. 2, end face 38 of head 34 is positioned between the planes of face 26 and face 28, as shown by the dot-and-dash line in Fig. 2. Therefore, when face 26 is in face-to-face contact with a surface, end face 38 will not be engaged by that surface, and plug 36 will not be displaced. However, when head 16 is turned along the line 40 of junction between faces 26 and 28 to move face 26 out of face-to-face contact with the surface, end face 38 will move into engagement with the surface upon which line 40 rests, and plug 36 will be compelled to move to a position within section 22.

Plug 36 consists of a slab of molded plastic material having a flat face 42 which forms a boundary wall for the plug, and extends all the way from end face 38 of head 34 along the enlarged body 44 of the plug down to recess 46 at the bottom 48 of the plug. Body 44 is positioned entirely within hollow section 22. At the junction between body 44 and head 34, the plug is reduced to form a ledge 50. Opening 30 is of such form and dimensions that it conforms closely to those of body 44 just immediately below ledge 50, and thus is just too small to permit the plug, once it is in the position shown in Fig. 2, to move through opening 30 and out of hollow section 22.

In hollow section 22, and on wall 32, a ledge 52 is provided directly below and in line with opening 30. A pin 54 extends upwardly from that ledge, and is positioned in line with and to enter recess 46. In fact, recess 46 is shaped to conform closely to the shape of pin 54, and thus pin and recess, when engaged, serve to guide the plug in its reciprocating movement in opening 30. By reason of the engagement of face 56 of recess 46 with face 58 of pin 54, no movement of plug 36 away from engagement of face 42 with face 60 of wall 32 may occur. Opening 30, as shown, is substantially rectangular. Plug 36, where it passes through opening 30, likewise is rectangular. Since opening 30 is slightly larger in one of its dimensions than plug 36, plug 36 is retained against movement in three directions by engagement with the edges of opening 30, while movement in the other direction is prevented by engagement of wall 62 of the plug between wall 32 and pin 54.

A spring 64 may be seated on ledge 52 to encircle pin 54 and extend up into engagement with plug 36. The plug may be formed with a depending portion or skirt 66 to form a retaining wall to retain the spring in position, the spring otherwise engaging against bottom face 68 of the plug. The plug is propelled by the spring through opening 30 to bring ledge 50 into engagement with the inner face 70 at opening 30. On engagement of end face 38 with a surface to which the mucilage is to be applied, the plug is caused to move into section 22 so that ledge 50 will be displaced from engagement against face 70, and so that fluid will be displaced from within the hollow section and will flow past the opening provided by the separation of ledge 50 from face 70, and out upon the surface to be coated. Then, by rocking the bottle on line 40 as a fulcrum, face 26 may be brought into position to spread the material.

In assembling plug 36 with head 16, spring 64 is first positioned on ledge 52 to encircle pin 54. Then bottom 48 of the plug is inserted through opening 30. The wedge face 72 of the plug then will engage against edge 74 of opening 30, and, as the plug is forced further into opening 30, face

72 will function to cam edge 74 slightly inwardly as ledge 50 approaches end face 28. Finally, ledge 50 will pass edge 74, permitting the material of the molded head at edge 74 to spring back into position. Then pin 54 and recess 46 will function to retain the plug snugly seated against face 60 so that the plug will be capable of reciprocation easily, without danger of separation of the plug from the head.

10 In Fig. 5, a modified construction is shown. In this case, a short pin 76 is formed on ledge 78. End 80 of plug 82 is formed substantially flat, with a flange 84 at one edge. A spring 86 encircles pin 76 and rests on ledge 78, and is in engagement with bottom 88 of plug 82, being retained by flange 84. In the structures here shown, mucilage, which may have come between plug and ledge during the stages of ejecting mucilage from the bottle and of spreading the mucilage, will, after the bottle is returned to its normal position, flow back into the bottle off ledge 78 and from the recesses in the bottoms of the plugs so that further operation of these parts may ensue without hindrance from the dried out solids of 20 accumulated mucilage. Also, as mucilage, which has remained on face 26 after the application to a surface, dries out, it will not tend to remain adhered to that face, but will separate in flakes from the surface, leaving the surface substantially at 25 all times clean and ready for use in making a clean application to a surface.

Many other changes could be effected in the particular apparatus designed, and in the method of operation set forth, and in specific details 30 thereof, without substantially departing from the invention defined in the claims, the specific description being merely of operative embodiments capable of illustrating certain principles of the invention.

What is claimed as new and useful is:

1. A dispensing spreader for fluid, the spreader comprising a body having an end wall and a side wall forming a cavity therewithin, the end wall having an opening therethrough immediately adjacent the side wall to provide a passage for fluid, flow-controlling means cooperating with and movable into and out of flow-cut-off position with relation to the opening, and means between the flow-controlling means and the body to guide the flow-controlling means in its movements with relation to the opening, the guiding means being arranged to provide drainage for fluid away from the operating parts of the flow-controlling means and the guiding means when the dispensing spreader is normally inoperative.

2. A dispensing spreader for fluid, the spreader comprising a body having an end wall and a side wall forming a cavity therewithin, the end wall having an opening therethrough immediately adjacent the side wall to provide a passage for fluid, a shoulder on the side wall within the cavity and in alignment with the opening, means reciprocating on the line between the shoulder and the opening to move into and out of flow-cut-off position with relation to the opening, and means between the reciprocating means and the shoulder to guide the reciprocating means in its movements with relation to the opening, the guiding means being arranged to provide drainage for fluid away from the operating parts of the reciprocating means and the guiding means when the dispensing spreader is normally inoperative.

3. A dispensing spreader for fluid, the spreader comprising a body having an end wall and a side wall forming a cavity therewithin, the end wall

having an opening therethrough immediately adjacent the side wall to provide a passage for fluid, and a plug cooperating with and movable into and out of flow-cut-off position with relation to the opening, the plug being supported and having a surface bearing against the side wall within the cavity and being guided thereby in its movements with relation to the opening, the plug and the support therefor being arranged to provide drainage for fluid away from the plug and the support therefor when the dispensing spreader is normally inoperative.

4. A dispensing spreader for fluid, the spreader comprising a body having an end wall and a side wall forming a cavity therewithin, the end wall having an opening therethrough immediately adjacent the side wall to provide a passage for fluid, and a plug cooperating with and movable into and out of flow-cut-off position with relation to the opening, the plug being supported and having a surface bearing against the side wall within the cavity and being guided thereby in its movements with relation to the opening.

5. A dispensing spreader for fluid, the spreader comprising a body having an end wall and a side wall forming a cavity therewithin, the end wall having a pair of substantially planar faces, the faces being angularly disposed with relation to each other to define substantially an obtuse angle therebetween, one of the faces having an opening therethrough to provide a passage for fluid, the opening being located adjacent an edge of that face removed from the other faces, flow-controlling means cooperating with and movable into and out of flow-cut-off position with relation to the opening, and means between the flow-controlling means and the body to guide the flow-controlling means in its movements with relation to the opening, the guiding means being arranged to provide drainage for fluid away from the operating parts of the flow-controlling means and the guiding means when the dispensing spreader is normally inoperative.

6. A dispensing spreader for fluid, the spreader comprising a body having an end wall and a side wall forming a cavity therewithin, the end wall having a pair of substantially planar faces, the faces being angularly disposed with relation to each other to define substantially an obtuse angle therebetween, one of the faces having an opening therethrough to provide a passage for fluid, the opening being located adjacent an edge of that face removed from the other face, and flow-controlling means cooperating with and movable into and out of flow-cut-off position with relation to the opening, the spreader being adapted to be approached to a surface upon which the fluid is to be spread to engage the flow-controlling means and cause flow of fluid onto the surface, the planes of the faces, when the flow-controlling means is so engaged, being both disposed at substantially acute angles to the surface, but the face having the opening therein being at an angle less than the angle of the other face, the flow-controlling means being located substantially at the apex of the angle formed by the plane of its face and the surface.

7. A dispensing spreader for fluid, the spreader comprising a body having an end wall and a side wall forming a cavity therewithin, the end wall having a pair of substantially planar faces, the faces being angularly disposed with relation to each other to define substantially an obtuse angle therebetween, one of the faces meeting the side wall to form substantially an acute angle and hav-

ing an opening therethrough substantially at the apex of the angle to provide a passage for fluid, a shoulder on the side wall within the cavity, a plunger having a portion thereof positioned within the cavity and a head thereof extending through the opening, the portion within the cavity having a section larger in cross-section than the opening, the plunger being supported against the side wall within the cavity and being guided thereby, the spreader being adapted to be approached to a surface upon which the fluid is to be spread to engage the flow-controlling means and cause flow of fluid onto the surface, the planes of the faces, when the flow-controlling means is so engaged, being both disposed at substantially acute angles to the surface, but the face having the opening therein being at an angle less than the angle of the other face, and means between the plunger and the shoulder to guide the plunger in its movements with relation to the opening, the plunger and the shoulder being arranged to provide drainage for fluid away from the plunger and the shoulder when the dispensing spreader is normally inoperative.

8. A dispensing spreader for fluid, the spreader comprising a body having an end wall and a side wall forming a cavity therewithin, the end wall having a pair of substantially planar faces, the faces being angularly disposed with relation to each other to define substantially an obtuse angle therebetween, one of the faces meeting the side wall to form substantially an acute angle and having an opening therethrough substantially at the apex of the angle to provide a passage for fluid, a shoulder on the side wall within the cavity, a plunger having a portion thereof positioned within the cavity and a head thereof extending through the opening, the portion within the cavity having a section larger in cross-section than the opening, the plunger being supported against the side wall within the cavity and being guided thereby and having a recess formed therein, the spreader being adapted to be approached to a surface upon which the fluid is to be spread to engage the flow-controlling means and cause flow of fluid onto the surface, the planes of the faces, when the flow-controlling means is so engaged, being both disposed at substantially acute angles to the surface, but the face having the opening therein being at an angle less than the angle of the other face, means between the plunger and the shoulder to guide the plunger in its movements with relation to the opening, and resilient means retained between the shoulder and the recess in the plunger, the plunger and the shoulder being arranged to provide drainage for fluid away from the plunger and the resilient means when the dispensing spreader is normally inoperative.

9. A dispensing spreader for a fluid receptacle comprising a hollow body formed to be fitted upon the mouth of a receptacle, the outside contour of the body including an applicator face, the body having an opening therethrough to provide a passage for fluid from the receptacle to the applicator face, a plug cooperating with the opening, the plug extending through and being slidable through and guided within the opening, the plug having an enlarged section greater in extent than the extent of the opening, the plug and the body having interfitting means for guiding the plug in its movement, and means cooperating with the interfitting means to project the plug for bringing the enlarged section into engagement with

the body at the opening to seal the opening against passage of fluid to the face.

10. A dispensing spreader for a fluid receptacle comprising a hollow body formed to be fitted upon the mouth of a receptacle, the outside contour of the body including an applicator face, the body having an opening therethrough to provide a passage for fluid from the receptacle to the applicator face, a plug cooperating with the opening, the plug extending through and being slid-
able through and guided within the opening, the plug having an enlarged section greater in extent than the extent of the opening, the plug having a recess therein, a pin within the hollow of the body and extending into the recess for guiding the plug in its movement, and means cooperating with the pin and the recess to project the plug

for bringing the enlarged section into engage-
ment with the body at the opening to seal the opening against passage of fluid to the face.

AUG. M. MAZZARELLI.
